GEORGE F. SCHNELL, OF DIAMOND SPRINGS, CALIFORNIA, ASSIGNOR TO MARTIN AIR DOG COMPANY, OF SAN FRANCISCO, CALIFORNIA, A CORPORATION OF CALIFORNIA.

DOGGING DEVICE.

Application filed December 23, 1926. Serial No. 156,667.

This invention is directed to stop means operative more particularly with dogging mechanism for the knees of saw mill carriages whereby in any and all possible adjustments of such knees and dogging mechanism, the dogs will be prevented from projecting into the saw line.

Conventionally, a saw mill carriage is provided with two or more knees which are adjustable on the carriage through the use of the set works for gradually advancing the log or cant to the saw for the sawing operation. These knees are provided with dogs, so-called, which are elements operated in various ways for engaging the upper and lower portions of the log or cant and holding the same in more or less fixed relation to the knee while the saw is operating to make the successive cuts in such log or cant. The so-called dogging devices have been devised in different forms and arrangements, in some instances being operative in advance of the knee on a particular line for the most effective engagement with a log. In other instances the dogs have been arranged so that they may be selectively positioned for operation beyond the face of the knee in either of two predetermined paths, one being that at which the dog is projected at the maximum distance beyond the face of the knee and thus serviceable for engaging round logs, and another being that in which the dogs are withdrawn for operation in a path at a minimum distance beyond the face of the knee and thus serviceable for engaging boards or cants. Furthermore, in those types of devices where the dogs are adapted for either a maximum or minimum position selectively, various types of mechanisms have been provided for securing this selective maximum or minimum position.

In order, therefore, to provide a means for so limiting the mechanism that the dogs cannot be projected into the path of the saw, it is apparent that the problem is one of accommodating the limiting means to the several varieties of dogging mechanisms both wherein the dogs operate in a fixed plane only and wherein the dogs operate in either a maximum or minimum plane at will.

The invention, therefore, consists in providing means whereby the dogs are prevented from reaching the saw line in any possible movement of the knee and without regard to the fact as to whether the dogs are capable

of only a single path of movement beyond the knee or are capable of a maximum or minimum path of movement beyond the knee.

The invention is illustrated in the accompanying drawings, wherein:

Figure 1 is a view in elevation of a particular type of dogging mechanism wherein the dogs are adapted for maximum or minimum positions, with the improved stop arranged to prevent the dogs in either position from reaching the saw line.

Figure 2 is a view in elevation of another type of dogging mechanism wherein the dogs are adjustable for movement in a maximum or minimum position, the improved stop in this instance serving to limit the movement of the knee with the dogs in either position to prevent the dogs entering the saw line.

Figure 3 is a similar view of another construction wherein the dogs are adjustable for a maximum or minimum path of movement relative to the knee, the improved stop in this instance being arranged to function to prevent the dogs reaching the saw line in either of their adjusted positions.

Figure 4 is a similar view of another type of mechanism wherein the dogs are capable of a single path of movement in advance of the knee, the stop in this instance serving to limit the movement of the knee so that the dogs in their projected positions will not encroach upon the saw line.

Figure 5 is a longitudinal sectional view on line 5—5 of Figure 1 showing the lower end of the guide in cooperation with the stop on the head block.

Figure 6 is a broken perspective of the head block showing the stop formation.

It is to be understood that the present invention may be defined as a stop or limiting means with which a selected part or parts of the apparatus on the knee will cooperate so that the dogs, when in operative position, cannot reach the saw line. The various constructions illustrated in the accompanying drawings are well known practical constructions for accomplishing the dogging operation, such constructions as illustrated in Figures 1, 2 and 3 being similar for the purposes of the present invention in that they provide for adjusting the dogs for a path of travel at a maximum distance beyond the face of the knee or for a path of travel at a minimum distance beyond the face of the knee; while the construction shown in Figure 4 provides

for only one path of movement of the dogs beyond the face of the knee. It will be obvious that as the constructions wherein the dogs are capable of the two independent paths, as in Figures 1, 2 and 3, provide for this dog adjustment through materially different instrumentalities and details, the problem of providing a stop effective with these respective mechanisms must necessarily embody different details, hence the different constructions are made with a view to illustrating the invention in connection with different types of dogging mechanisms. The respective dogging mechanisms shown in the drawings will be but briefly described with that description limited largely to the details necessary for the understanding of the present invention, it being understood that the constructions shown are actually practical working constructions and have been commercially practiced as dogging mechanisms, no claim being made in this application concerning the specific dogging mechanism, except in its application to my improvement.

In the form shown in Figure 1, the knee indicated at 1 is mounted for movement on a head block 2 in any usual or preferred manner, the knee being thus adjustable to and from the saw line indicated in dotted lines at 3. The dogs proper indicated at 4 are mounted upon a bar 5 which, through the medium of angle levers 6, power lever 7 and power means 8, is adjusted to and from the face of the knee, whereby the dogs may operate at a maximum path beyond the face of the knee or at a minimum path beyond such knee face. As the knee is ordinarily adjustable longitudinally of the head block and toward the saw line in an identical manner and to the same extent without regard as to whether the dogs are adjusted for maximum or minimum operation, it will be evident that the knee cannot be directly limited or stopped, for if the knee were limited to prevent the dogs when in minimum position from reaching the saw line, such knee limit would not prevent the dogs in maximum position from reaching the saw line. Hence the knee may be said to be the fixed factor in the dog adjustment, that is the distance movement of the knee relative to the saw line being a fixed and not a variable movement in accordance with the dog adjustment, such knee cannot be directly stopped. However, there is a member—here the bar 5—which is variable, that is this bar has a variable position relative to the knee in accordance with the dog adjustment. If, therefore, this variable factor be utilized as the stop element, and thus limit the knee movement, it follows that the correspondence being the movement of the variable factor and the position of the dogs, will serve to always limit the knee movement to hold the dogs from the saw line no matter what the particular dog projection may be. Obviously,

therefore, the knee remains a fixed factor in the adjustment and the position of the dogs relative to the face of the knee is controlled by the movement of the bar 5, hence this bar 5 is the variable factor in the adjustment. If the stop means of the present invention was applied on the knee so as to specifically limit the knee, it is apparent that if the dogs in their minimum path were prevented from reaching the saw line by the cooperation of the knee with the improved limiting means, then such dogs, when projected for their maximum path beyond the face of the knee, would encroach upon the saw line, for it is understood that the article held by the dogs against the knee is gradually advanced by the movement of the knee to the saw line for successive cuttings. It is apparent, therefore, that in this particular form the variable factor in the adjustment of the dogs must be the member controlled by the stop element, hence for the purpose of the present invention, the bar 5 is extended below the lower dog and below the knee to provide an abutment 9 and there is secured upon the head block in the path of movement of this abutment a fixed stop 10. Therefore, the advance of the knee to adjust a log or board to the saw line is stopped when the abutment 9 on the bar 5 engages the stop 10. As the position of the bar 5 relative to the knee determines the operative projection of the dogs beyond the face of the knee, it is apparent that the abutment 9 is always adjusted with respect to the face of the knee in accordance with the adjustment of the dogs, that is to say that if the dogs are advanced to their maximum, the abutment 9 will be closer to the face of the knee than if the dogs are withdrawn to their minimum position. Hence the abutment on the bar 5 will always engage the stop in the same relative position of the knee with respect to the saw line. That is, if the dogs are projected to their maximum, the movement of the knee will be interrupted farther from the saw line than if the dogs are projected to their minimum positions, hence the dogs, whether projected at their maximum or minimum, cannot reach the saw line.

Figure 2 illustrates another type of apparatus in which the dogs are capable of maximum or minimum path of movement beyond the face of the knee. Here the knee, indicated at 11, is mounted upon the head block 12 for the usual movement. The dogs 13 are vertically guided in a guide 14, which guide is bodily movable longitudinally of the knee in guide channels or slots 15. Through mechanism indicated generally at 16, and not requiring any specific description, the dogs may be adjusted to a position for maximum projection beyond the face of the knee or for minimum projection, this movement of the dogs serving to move the vertical guide 14 in the guide channels 15 to and from the face

of the knee for controlling the predetermined path of movement of the dogs. Here, as in the form shown in Figure 1, I have a variable factor in the dog adjustment, such in this 5 instance being the movable guide 14. Thus the movable guide, being the variable factor in the adjustment, is for the purpose of the present invention, extended to form an abutment 17 which is arranged to cooperate with 10 a stop 18 fixed on the head block. Therefore, no matter what the position of the guide, that is no matter what the projection of the dogs beyond the face of the knee, the guide abutment 17 will cooperate with the stop 18 to 15 limit the movement of the knee in direct accord with the position of the guide, that is the projection of the dogs in any particular instance.

In the form shown in Figure 3 there is provided an additional construction wherein the 20 dogs are capable of being adjusted for movement in a maximum path beyond the face of the knee or in a minimum path beyond such knee face. In this form, the knee indicated 25 at 19 is mounted for movement on the head block 20 in the usual manner. The dogs 21 are bodily slideable through castings 22 which are guided, in the vertical movement of the dogs, in a guide 23 fixed to the knee. The adjustment of the dogs to secure their maximum 30 or minimum operation is secured by bodily moving the dogs through the castings 22, the latter remaining at all times in guiding cooperation with the guide 23. This bodily movement of the dogs is secured through 35 mechanism indicated at 24 and which may be, for the purposes of this description, referred to as a connecting plate 25 to which both of the dogs are directly or indirectly connected, 40 with such plate capable of moving in substantially rectilinear lines through pivoted links 26. Here again, we have a variable factor in the adjustment of the dogs; that is to say the plate 25 which follows the movement 45 of the dogs in that it occupies one position relative to the knee in the maximum adjustment of the dogs and another position in the minimum adjustment of the dogs. Therefore, in the present invention the stop forming 50 the present improvement is constructed as a lug 27 depending from the plate 25 and adapted to cooperate with a stop 28 on the head block. Of course, it is understood that the lower dog is also a variable factor in the 55 adjustment and the lug 27 may, if desired, depend directly from this lower dog, preferably near its pivotal support. Obviously in this form the movement of the variable factor correspondingly positions the lug 27 60 with respect to the face of the knee and hence the stopping function of said lug, when cooperating with the stop 28, will limit the further movement of the knee in direct accord to the position of such lug with respect to the 65 face of the knee. The position of the lug 27,

of course, is directly controlled by the position of the variable factor of the adjustment and hence, no matter what the projection of the dogs may be in the particular instance, the movement of the knee will be so limited 70 that such dogs cannot reach the saw line.

In Figure 4 there is shown a construction in which the dogs are limited to a single path of movement beyond the face of the knee. In this form the knee 29 cooperates with a 75 head block 30 in the usual manner and is provided with a fixed guide 31 in which the dogs 32 are movable through mechanism indicated generally at 33 and requiring no specific description for the purposes of this invention. 80 Here the dogs only have one path of movement beyond the face of the knee. There is no variable factor in the dog movement because the dogs are not capable of more than one operative path in advance of the face of 85 the knee. Therefore, the knee, if interrupted in its advancing movement at a point which will prevent the dogs in their single path of movement from reaching the saw line, will carry out the purposes of the present invention. 90 To economically and practically provide for this result, the fixed guide 31 is extended below the knee as an abutment 34 which is adapted, in the movement of the knee, to cooperate with a stop 35 on the head 95 block. The knee cannot advance beyond the limit position defined by the cooperation of the abutment 34 and stop 35. As the dogs are movable only in one path in advance of the knee and as the position of the stop 35 is 100 such as to interrupt the advancing movement of the knee before the dogs in their one operative position reach the saw line, it is apparent that such dogs cannot interfere with the operation of the saw.

It is to be understood that the various forms here shown are indicative of several types of mechanisms in which provision is made for either operating the dogs in a single path of movement or adjusting the dogs so 110 that they may operate in a maximum or minimum path of movement. The mechanisms are illustrated merely to indicate the adaptability of the present invention to such mechanisms, it being understood that the invention as contemplated by the appended claim comprehends the relation of the movable stop, that is the element of the improved stop which is carried by and movable with the knee, to the variable factor permitting the 115 dog adjustment as will utilize this factor as the movable stop element. Thus the adjustment of the dogs controls the position of the knee-carried element of the stopping mechanism.

What is claimed as new is:

In a saw mill carriage, a head block, a knee movable thereon, a dog-carrying frame arranged substantially parallel to the face of the knee and mounted for movement relative 130

to such face, a dog carried by and movable relative to such frame, means for moving the frame toward and from the face of the knee to adjust the dog for maximum or minimum projection beyond the face of the knee, and a stop on the head block, the dog-carrying frame providing a stop to cooperate with the stop on the head block when the knee has reached a position in its movement toward the saw line which will prevent the dog from

encroaching on the saw line in either its minimum or maximum projection, the adjustment of the frame relative to the face of the knee determining the position of the knee-carried stop and of the projection of the dog ¹⁰ beyond the face of the knee in relative accordance.

In testimony whereof I affix my signature.

GEORGE F. SCIINELL.
